Atty.

UNITED STATES PATENT OFFICE.

JOSEPH TERR, OF CUYAHOGA FALLS, OHIO, ASSIGNEE TO THE MARATHON TIRE & RUBBER COMPANY, OF CUYAHOGA FALLS, OHIO, A CORPORATION OF OHIO.

BAG.

1,419,425.

Specification of Letters Patent. Patented June 13, 1922.

Application filed August 22, 1921. Serial No. 494,332.

To all whom it may concern:

Be it known that I, JOSEPH TERR, a citizen of the United States of America, residing at Cuyahoga Falls, in the county of Summit 5 and State of Ohio, have invented new and useful Improvements in Bags, of which the following is a specification.

This invention relates to bags for holding 10 golf clubs and like uses and more particularly to a golf bag or the like produced of a moldable composition such as rubber compound with suitable reinforcements.

A principal object of the invention is to provide a golf bag that may be cast, molded 15 or formed in one piece as a unit, and including in the molded formation, a plurality of vertical stays which reinforce the bag longitudinally, and also the collar and collar rim at the top of the bag, and the bottom ring 20 and base of the bag.

In accordance with my invention the bag bottom, which is molded as a part of the one-piece unit, has embedded therein a reinforcement of special material somewhat 25 harder than the rest of the bag and so designed as to resist the impact of the clubs or other articles. This reinforcing material is at the same time resilient enough to avoid unnecessary and unpleasant metallic sounds 30 and so as to cause no injury to the clubs when dropping them into the bag. The foregoing and other objects and advantages of the invention will more fully appear from the following detailed description, and the 35 distinctive feature of novelty will be pointed out in the appended claims.

Referring to the drawings:

Figure 1 is a side elevation of a golf bag embodying the invention; 40 Fig. 2 is a transverse section on a relatively enlarged scale, on line 2—2 of Fig. 1; and

Fig. 3 is a longitudinal vertical section on the same scale as Fig. 2, and with an intermediate portion broken away. 45

10 indicates the body of the golf bag which may be made of a dimension to receive a usual set of golf clubs, and as illustratively shown, of circular cross section. 50 This body is produced of a suitable composition capable of being cast or molded, certain rubber compounds being suitable for the purpose, and it has molded therewith, as a one-piece unit, a top collar or band 11 with 55 a collar ring or bead 12 at its upper ex-

tremity, and also a bottom reinforcing collar or band 13. The bag bottom 14 is molded as a part of the one-piece unit, substantially thicker than the side walls and with a reinforcing layer 15 embedded therein. This 60 reinforcing layer or sheet may be of any suitable material, somewhat harder than the rest of the bag, and with a toughness to resist the impact of the clubs. Vulcanized canvas or fiber is suitable for this purpose 65 though other materials may be used.

Molded also as a part of the one-piece unit are a plurality of vertical stays or ribs extending the length of the bag between the end collars 11, 13. Two such vertical stays 70 are herein indicated at opposite sides of the bag, these appearing as ribs 16 exteriorly of the bag. Incorporated in this bag or unit is an interior carcass of strong fabric such as canvas indicated at 17 and lining the entire interior of the bag, thus giving reinforcement at all necessary points. 75

In the preferred process of manufacture, the entire bag is built up in the uncured state, then placed in a mold which gives the 80 outer contour to the bag; the hollow of the bag is formed by inserting into the uncured, but built up bag, what is known as an air bag, previous to closing the mold. When pressure and heat are turned on in the curing process, air is injected into this air bag at a pre-determined pressure which forces the material with great pressure against the inside of the mold, thus insuring a uniform 85 and perfect cure. 90

In the practice of the invention, the bag may be made either with a smooth outer surface or with any suitable grain representing leather or any other kind of surface. The bag thus produced may have attached 95 thereto a ball pocket 18, shoulder straps 19, and a handle 20, all these parts being preferably made of moldable rubber composition which may be the same as that of the body of the bag; these parts may be attached 100 either by stitching or riveting, the straps being preferably riveted, and the ball pocket stitched to the bag body. I am aware that the invention may be embodied in other specific forms without departing from the 105 spirit or essential attributes thereof, and I therefore desire the present embodiment to be considered in all respects as illustrative and not restrictive, reference being had to the appended claims rather than to the fore- 110

going description to indicate the scope of the invention.

Having described my invention, what I claim as new and desire to secure by Letters 5 Patent is:

1. A golf bag or the like molded as a one-piece unit with end collars and vertical stays included as parts of the molded unit.
2. A golf bag or the like comprising a 10 body reinforced interiorly by fabric with end collars, a reinforced bottom, and vertical stays, all molded as a one-piece unit.
3. A golf bag or the like comprising a

body reinforced interiorly by a fabric lining with collars at top and bottom, a reinforced 15 bottom, opposite vertical stays extending the length of the bag and a top bead, all formed and molded as a one-piece unit and vulcanized.

In testimony whereof I affix my signature 20 in presence of two witnesses.

JOSEPH TERR.
